UNITED STATES PATENT OFFICE.

DE WITT B. WILLIAMS, OF PRESCOTT, ARIZONA.

CAR.

SPECIFICATION forming part of Letters Patent No. 470,089, dated March 1, 1892.

Application filed October 21, 1891. Serial No. 409,364. (No model.)

To all whom it may concern:

Be it known that I, DE WITT B. WILLIAMS, of Prescott, in the county of Yavapai and Territory of Arizona, have invented a new and 5 Improved Car, of which the following is a full, clear, and exact description.

The object of the invention is to provide a new and improved railroad-car adapted to be readily transformed from a box-car to an open 10 car, and vice versa, and if used as a box-car be readily opened at any part to unload some of the contents without disturbing the rest.

The invention consists of a platform carrying corner-posts connected at their upper ends 15 by a band, and a series of side doors hung on the said band and adapted to be fastened at their lower ends to the side of the platform.

The invention also consists of certain parts and details and combinations of the same, 20 which will be fully described hereinafter, and then pointed out in the claims.

Reference is to be had to the accompanying drawings, forming a part of this specification, in which similar letters of reference indicate 25 corresponding parts in both the figures.

Figure 1 is a side elevation of the improvement arranged as a box-car, and Fig. 2 is a a transverse section of the same on the line 2 2 of Fig. 1.

30 The improved railroad-car is provided with a platform A, mounted in the usual manner on wheels and carrying in its four corners posts B, connected with each other at their upper ends by a rectangular band C, preferably made of metal of suitable thickness to support a roof D, formed with a flange D', engaging the inner side of the band C, thus preventing leakage and at the same time forming means for holding the roof in place.

40 On the top of the roof on the usual running-board are secured a series of eyes or hooks E, adapted to be engaged by the chains of the derrick or other hoisting apparatus for lifting off the roof D or placing it on the band, for 45 the purpose hereinafter more fully described.

The ends of the car are preferably made solid with a suitable boarding, while the sides of the car are formed by a series of doors F, preferably overlapping one another, as is 50 plainly shown in Fig. 1, so as to form a tight bind on adjacent doors. The upper end of

each door F is formed with an L-shaped flange F', engaging a slot C', formed longitudinally in the respective side of the band C, the said slot permitting the door to hang 55 in a vertical position, as is plainly shown in Fig. 1, and to the left in Fig. 2, and the slot also permits of sliding the door into a horizontal position, as shown to the right in Fig. 2, the door then being supported in the upper 60 part of the car on suitable longitudinally-extending rods G, held in sockets or other means in the ends of the car. The lower end of each door F is formed with an outwardly-projecting flange F'', and the lower end is adapted to 65 be engaged by a longitudinally-extending locking-bar H, connected at one end by a link I to the respective corner-post B, the other end of the locking-bar being fastened in place to a middle post B' by a padlock J or other 70 locking device. Instead of using the middle post B', the bar H may extend from one end of the car to the other, the padlock then being applied on the free end of the bar on the corner-post. Owing to the considerable length 75 of the cars as now constructed, it is preferred to employ a middle post B' to conveniently and strongly support the band C and to shorten the locking-bars H.

When it is desired to use the car as a box- 80 car, the several parts are in position, as shown in the drawings. When the locking-bars H are unlocked, any of the doors F can be opened by swinging the door first outward into nearly a horizontal position and then shifting it 85 transversely, so that the door slides over the longitudinally-extending rods G to support the door in an uppermost position inside of the car. Thus any part of the car can be readily loaded or unloaded without disturbing 90 the rest of the car or the contents loaded therein. If desired, the entire top or roof D can be removed by a suitable hoisting device, so that long articles can be conveniently placed in the car from above through the open 95 top. The rods G are held removably in the sockets in the ends of the car, so as to be readily taken out when the car is to be changed to a platform or open car. To change the car to a platform or open car, the top is first removed, then the doors are taken off the band C, then the corner-posts may be removed with 100

the band, if desired. Ordinarily the corner-posts, as well as the band C, may remain on the car.

Having thus described my invention, I claim as new and desire to secure by Letters Patent—

1. A car comprising a platform, corner-posts erected on the said platform, a band connected with the corner-posts, and a series of side doors hung on the said band and adapted to be fastened at their lower ends to the side of the platform, substantially as described.

2. A car comprising a platform, corner-posts erected on the said platform, a band connected with the corner-posts, a series of side doors hung on the said band and adapted to be fastened at their lower ends to the side of the platform, and means, substantially as described, for fastening the lower ends of the doors in place on the platform, as set forth.

3. A car provided with a band supported on corner-posts and a roof supported on the said band and bodily removable from the car, whereby it is adapted to be lifted off, substantially as described.

4. A car provided with a band supported on corner-posts, a roof supported on the said band and adapted to be lifted off, and a flange formed on the under side of the said roof, engaging the said band, substantially as described.

5. A car provided with a band supported on corner-posts, a roof supported on the said band and adapted to be lifted off, and hooks or eyes for hoisting the said roof, substantially as described.

6. In a car, the combination, with a band supported on corner-posts and formed with longitudinal slots, of a series of doors formed at their upper ends with flanges engaging the said longitudinal slots, substantially as described.

7. In a car, the combination, with a band supported on corner-posts and formed with longitudinal slots, of a series of doors formed at their upper ends with flanges engaging the said longitudinal slots and longitudinal rods arranged in the upper part of the car and adapted to support the said doors, substantially as described.

8. In a car, the combination, with a band supported on corner-posts and formed with longitudinal slots, of a series of doors formed at their upper ends with flanges engaging the said longitudinal slots and a locking device for fastening the lower ends of the said doors in place, substantially as described.

DE WITT B. WILLIAMS.
